R. J. THOMPSON.
RULING APPARATUS.
APPLICATION FILED MAR. 2, 1920.

1,370,565.

Patented Mar. 8, 1921.

UNITED STATES PATENT OFFICE.

ROBERT J. THOMPSON, OF HARRISBURG, PENNSYLVANIA, ASSIGNOR TO W. O. HICKOK MANUFACTURING COMPANY, OF HARRISBURG, PENNSYLVANIA, A CORPORATION OF PENNSYLVANIA.

RULING APPARATUS.

1,370,565.

Specification of Letters Patent.

Patented Mar. 8, 1921.

Application filed March 2, 1920. Serial No. 362,879.

To all whom it may concern:

Be it known that I, ROBERT J. THOMPSON, a citizen of the United States, residing at Harrisburg, in the county of Dauphin and 5 State of Pennsylvania, have invented certain new and useful Improvements in Ruling Apparatus, of which the following is a specification.

The present invention relates more particularly to the conveying means of ruling apparatus. As is well known a considerable 10 interval of time should elapse after the lines are ruled before the sheets are piled, to permit the ink to set or dry, and thus obviate 15 smearing.

The object of the present invention is to provide a novel and simple mechanism whereby the sheets will be carried past the ruling mechanism, and then over a relatively 20 long and tortuous path before the delivery means is reached, the sheets during their passage being effectively held by the conveying means.

An embodiment of the invention is illustrated in the accompanying drawings, 25 wherein:—

The figure is a longitudinal sectional view somewhat diagrammatic in its character 30 through a ruling machine having an embodiment of the invention as a part thereof.

A supporting frame is employed, a portion 35 of which is designated 3, and on said supporting frame is mounted a bed plate or table 4, the upper face of which is concaved in form. An endless work-carrying or conveyer belt 5 has an upper stretch 6 that moves longitudinally over the table 4, and has a lower return stretch 7. The belt passes around a rear roller 8 of relatively 40 large diameter and around a front driving drum or roller 9 actuated by any suitable source of power, not shown. A guide roller 10, located in advance of the table 4 and over the upper stretch 6, serves to hold the 45 portion of the belt in advance of said table in depressed relation so as to insure that the portion moving over the table is smooth and flat thereon. Supporting rollers 11 are interposed between the roller 9 and the roller 50 10 and serve to maintain the belt between the said rollers 9 and 10 in substantially concaved relation. The lower stretch 7 of the belt is guided by suitable rollers 12 and 13. A tension roller 14 is located slightly

below and in rear of the roller 9, the belt 55 passing around said roller on the opposite side to the roller 9.

Operating over the upper stretch 6 of the belt 5 are suitable ruling instrumentalities, comprising pens 15 carried by beams 16. It 60 is believed to be unnecessary to enter into detail regarding these instrumentalities, as they may be of any well known or desired character, though preferably of the type disclosed in co-pending application, Serial 65 No. 325,368, filed September 22, 1919. A suitable gage or gate 17, located over the central of the rollers 11 determines the passage of the sheets to the ruling devices.

In order to insure the proper movement 70 of the paper with the stretch 6 of the belt 5, endless holding cords or bands 18 have lower stretches that rest upon the outer face of the upper stretch 6 of the belt. These cords or bands pass around a roller 19 located above the roller 9, thence beneath the roller 10 and around a rear roller 20 located above the upper stretch of the belt 6 in advance of the rear roller 8. Suitably elevated guide rollers 21 and 22 support the 75 return upper stretches of the bands or cords and guides 23, adjustably mounted on a supporting rod 24, determine the positions of the cords or bands transversely of the belts.

The said endless conveyer belt 5 between the upper stretch 6 and lower stretch 7 is provided with an intermediate loop having an upper substantially horizontal stretch 26 and a lower return stretch 27. The rear or 90 open portion of the loop is determined by an upper guide roller 28 and a lower roller 29 of smaller diameter than the upper roller. The front or closed portion of said loop passes around the front side of a guide roller 95 30 of relatively large diameter. Another guide roller 31 is preferably located between the rollers 28 and 30 upon the upper surface of the upper stretch 26 of the belt.

Interposed between the upper and lower 100 stretches 26 and 27 of the loop are endless holding bands or cords 33, each having an upper stretch 34 extending longitudinally along and in coaction with the under face of the upper stretch 26 of the belt loop, and 105 furthermore having a lower stretch 35 located longitudinally upon and coacting with the upper face of the lower stretch 27 of

the loop. Cords or bands 33 at their rear ends pass around the roller 8 and against the outer face of the belt 5. They also pass around a guide roller 36 located above and 5 slightly in advance of the roller 8, thus providing a feeding throat in rear of the cords 18. The rear portions of the cords 33 are furthermore passed through guides 39 slidably mounted on a supporting rod 40, 10 the guides 39 determining the position of the cords transversely of the belt. The front portions of the cords or bands 33 pass around the roller 30, being interposed between said roller and the belt. Their rear 15 portions are furthermore guided by a roller 41 located adjacent to the roller 29 and by a guide roller 42 located between the roller 41 and the guide roller 28.

Inasmuch as the loop 26-27 terminates 20 short of the roller 8, the space left is occupied by coacting endless delivering bands 43 carried on pulleys 44. The adjacent coacting faces of said bands 43 are substantially in line with the coacting stretches 27 and 35.

The operation may be briefly outlined as follows. Sheets of paper, successively introduced between the rollers 9 and 19, are 30 caught by the coacting stretches 6 and 18, and when the gage or gate 17 is raised, are passed into the machine and beneath the ruling devices which mark the lines thereon. After passing the ruling apparatus they are 35 released from the cords 18 and are carried by the upper stretch of the belt to the drum 8. Here they are engaged between the belt 5 and the cords 33. They are consequently carried around the drum 8 and are held 40 against the under face of the upper stretch 26 of the loop by the upper stretches 34 of the bands or cords 33. They are thus carried back to the front of the machine, and obviously are securely held so that they are not 45 only maintained flat against any curling tendency due to the damp ink, but cannot be displaced by air currents or the vibration and jar of the machine. Reaching the front or closed end of the loop the papers are carried around the roller 30. They are now 50 moved again rearwardly upon the lower stretch 27 of the loop and are held thereon by the lower stretches 35 of the cords, being thus caused to again travel substantially the full length of the machine. At the rear 55 end of the loop, both the belt and the cords leave the paper at an acute angle, thereby avoiding any tendency of the sheets to bend and pass on with either. They consequently pass between the delivery bands 43 and are 60 carried thereby to suitable piling or depositing means.

From the foregoing, it is thought that the construction and operation and many advantages of the herein described invention will

be apparent to those skilled in the art, without further description, and it will be understood that various changes in the size, shape, proportion and minor details of construction, may be resorted to without departing from the spirit or sacrificing any 70 of the advantages of the invention.

Having thus fully described my invention, what I claim as new, and desire to secure by Letters Patent, is:—

1. In apparatus of the character described, the combination with an endless work-conveying belt having a feeding stretch and a return stretch and a looped conveying portion between said feeding and return stretches, ruling mechanism coacting 80 with the feeding stretch, and endless holding cords extending longitudinally within the loop and having stretches extending longitudinally along and respectively coacting with the opposite inner sides of the loop to 85 hold the work against both of said sides.

2. In apparatus of the character described, the combination with an endless work-conveying belt having a feeding stretch, a return stretch and a looped conveying portion between said feeding and return stretches, ruling mechanism coacting 90 with the feeding stretch, a guide roller at the inner end of the loop and about which the belt passes, and endless holding cords extending longitudinally within the loop and around the roller between said roller and the belt to hold the work against the belt while 95 in the loop.

3. In apparatus of the character described, the combination with an endless work-conveying belt having an upper feeding stretch, a lower return stretch and an intermediate loop interposed between the said stretches, a rear guide roller between 105 the upper feeding stretch and the upper stretch of the loop and around which the belt passes, a front guide roller between the upper and lower stretches of the loop and about which the belt passes, ruling mechanism coacting 110 with the feeding stretch, endless holding cords located above the feeding stretch and having lower stretches operating thereupon, and other endless cords extending around the rear guide roller outside the 115 belt and around the front guide roller between said roller and belt, said cords extending along and coöperating with the under face of the upper stretch of the loop and the upper face of the lower stretch of 120 the loop for holding the work thereagainst after it has passed the ruling mechanism.

In testimony whereof I affix my signature in the presence of two witnesses.

ROBERT J. THOMPSON.
